UNITED STATES PATENT OFFICE.

JUDSON McFELL, OF CHICAGO, ILLINOIS.

SELECTIVE SIGNALING SYSTEM.

1,048,561.

Specification of Letters Patent. Patented Dec. 31, 1912.

Application filed June 18, 1909. Serial No. 502,979.

To all whom it may concern:

Be it known that I, JUDSON McFELL, a citizen of the United States, residing at Chicago, in the county of Cook and State of Illinois, have invented certain new and useful Improvements in Selective Signaling Systems, of which the following is a specification.

My invention relates to improvements in selective signaling systems, and has for its general object to provide a selective signaling system especially adapted for railroad telephone service and the like.

One of the salient objects of my invention is to provide a single-line signaling system in which any suitable number of stations may be incorporated in the line energized by a single battery, wherein any station may call any other.

Another object of my invention is to provide a system whereby a signal initiator set to send a signal consisting of a plurality of impulse groups, and a release impulse, may actuate a different selector for each impulse group and restore all selectors to normal by the release impulse.

Among the salient features of my invention is the provision of a system in which each station is provided with means responsive to line conditions such as a single line relay responsive to simple make and break signals initiated in the line; and local circuit devices, comprising a plurality of selectors automatically operable in predetermined sequence in response to the line relay for predetermined collocation to actuate the translating device which effects the call of such station, and self-restoring to normal position on further operation of the line relay.

A further feature of my invention contemplates the automatic restoration of the selective devices to normal position after a partial operation of the selective system, the maintenance of the selectors in step, and the guarding of the local circuit devices against undue current-loss under abnormal conditions which might tend unduly to maintain the local circuit closed.

Many further features of my invention may best be gathered from the description of an embodiment thereof as shown in the accompanying drawings, in which—

Figure 1 is a diagrammatic view showing the circuit relations of parts constituting a system embodying my invention; Fig. 2 is

a front view of an instrument board equipped with apparatus suitable for the practice of my invention; Fig. 3 is a section on line 3—3 of Fig. 2; Fig. 4 is a schematic view of a transmission box; and Fig. 5 is a detail thereof.

In the embodiment of my invention, I provide a line in which the devices of the several stations are arranged preferably in simple series for energization from common means of current supply, the system which I have shown and prefer comprising a single wire line 10, provided at any suitable point with a battery 11, grounded at both ends and involving at each of the several stations A, B, and C (whereof any number may be provided) circuit-breaking signal-initiating means, and a line relay 12 having its coil in series in the line. This series arrangement is useful, for example, in railway telephone service where it is intended to use one wire only for signaling, but it will become apparent that some of the features of my invention are not concerned with the details of line-circuit arrangement.

A specific form of signal initiating means which I deem desirable for the best embodiment of my invention will be later described, but in its essence the signal initiator is simply a line-breaking switch or plurality of switches, and my system may be operated by a simple telegraph key or the like.

The normally energized line relay 12 constitutes the means of control of local devices and responds to the line-breaks effected by the signal initiating devices, the armature 13 of said relay 12, which stands normally against its front contact 14, being connected, as is also the back contact 15, in a local operating circuit. The local operating circuit has a local source of current supply 16 and comprises wire 17 connecting the positive terminal of the battery 16 with the armature 13, wire 18 connecting the back contact 15 with an operating magnet 19, wire 20 connecting the remaining terminal of said magnet with a cutout switch 21, and wire 22 connecting said switch with the remaining terminal of the battery 16.

The operating magnet 19 constitutes a convenient single electro-responsive instrumentality responsive, through relay 12, to the line signals for operating either of two selectors 23, 23', which I will hereafter term the "tens" and "units" selectors respectively, and which by their collocation in

predetermined positions are instrumental in causing the response of the translating device, such as a bell, the operation of which completes a call.

5 It will be apparent that while in some instances it is very desirable to relay operating actions from the line to the operating magnet 19, as by a line relay 12. These two devices, 12 and 19, operate in unison in 10 effecting the transfer of signal impulses from the line to the selector and, under ordinary signaling conditions, both operate in response to signaling conditions in the line, the relay 12 directly and the magnet 19 in 15 indirectly, or through said relay. The operating magnet 19 will obviously perform its function however it be connected with the line to operate in harmony with the signal impulses.

20 The selectors 25 and 25' comprise each a sector, 26, 26', toothed at its periphery for step by step operation against spring resistance and each having coöperating therewith a live or moving pawl and a dead or holding 25 pawl. The live pawls are independent of each other and are identical in construction, the structure for the sector 26 comprising an angular arm 27, pivoted as at 28, and extending to a position nearly centrally below 30 the magnet 19, the remote end of the arm 27 bearing the spring pressed pawl 29 which may, when the inner end of the arm is depressed, engage a tooth of the sector and advance it one step. The holding pawls for 35 the two sectors are of different construction for coöperative action. Thus the dead pawl 30 for the tens selector is of such construction that it tends by gravity to fall away from the sector and is normally maintained 40 in operating position by a spring 31 mounted on a laterally shiftable bar 32, guided at one end as at 33, and at its opposite extremity pivotally connected to the holding pawl 30' for the units selector which said pawl is 45 provided with a relatively stout spring 31'. The relation between these parts is such that the spring 31 presses against the pawl 30 only when the bar 32 is shifted to the left (in Fig. 2) so as to draw the pawl 30' for 50 the units selector out of operative relation to its toothed sector; and when said pawl 30' is moved into operative position by spring 31', the spring 31 of the tens pawl 30 is withdrawn from engagement with the said 55 pawl 30, leaving the latter under gravity control subject to the frictional engagement which it may have with a tooth of the sector. The movements of the shiftable bar 32 are controlled in part by both sectors, said bar 60 having thereon a pin 34, arranged to be engaged by the sector 26, to maintain its position shown in Fig. 2 when the selector 25 is in its normal position, and the selector 26' being provided with a pin 34' associated 65 with the end of the bar 32 to prevent its

shifting toward the right, when the units selector 25' is in normal position. Thus it will be apparent that the mechanical construction described is such that if the tens selector 25 be actuated, its holding pawl 30 70 performs its function as the selector advances step by step, but the pin 34 is freed by the movement of the sector 26, the bar 32 being maintained against shifting by the pin 34' on the units selector. 75

The movements of both of the live pawls 27 and 27' are controlled by the armature 35 of the operating magnet 19, said armature having connected thereto for universal movement a bar 36 which accordingly as it is shifted to left or right, may engage pins on either of the arms 27 or 27'. Thus it will be obvious that both selectors are operationally dominated by the single magnet 19, and that by the lateral shifting of the bar 36, either selector alternatively may be potentiated or conditioned for advancement or operation and the other disabled from operation. For controlling such alternative potentiation of the selectors, I provide an 80 electrical controlling means comprising suitable electrical circuits and devices including a shifting mechanism 40 which provide two electro-magnets, 41, 41', which I will term respectively the "tens controlling magnet" 85 and the "units controlling magnet," operating in conjunction with a common armature 42, which has an extension connected as at 43 with the shifting bar 36, so that when the armature stands attracted to "tens" magnet 41, the tens selector is conditioned for 90 advancing operation, and when the armature shifts over to the "units" magnet 41' the units selector is conditioned for operation. 95

The automatic shifting means 40 has its two magnets involved in parallel branches of the controlling circuit energized by the battery 16, controlled in common by the cut-out switch 21, and each branch having its 100 operative continuity subject to triple control, dependent first, upon the position of the armature 42 of the shifting device itself; second, upon the timing device or retard mechanism set in operation by the operating magnet 19; and third, upon the position of the sectors of the two selectors. For attaining this triple control, I provide 110 switches as follows: In conjunction with the armature 42 are arranged two switches 45 and 45', each having a long lower leaf arranged to be raised into contact with the upper leaf, the long lower leaves being disposed in conjunction with an insulating block 46 upon the armature 42, so that the 115 switches are alternatively closed, switch 45' being closed when the armature is attracted by magnet 41, and vice versa. Switch 45' likewise has an auxiliary bottom spring 45'' 120 closable with the elongated lower spring 130

when the latter breaks connection with its upper contact. Companion switches 47 and 47' are likewise provided beneath the magnet 19, each arranged to stand normally closed, with a lower leaf elongated and engaged by cross bar 48 carried upon the stem 48 of a dash pot 49, said stem 48 underlying and being engaged by a finger 50 projecting rearwardly from the armature bar 36 of the magnet 19. Thus whenever the magnet 19 attracts its armature 35, both switches 47 and 47' are opened, the dash pot yielding readily in such direction to permit the action to be free, but operating to retard the automatic reclosing of the switches for a suitable length of time greater than the interval allotted between the transmission of two signal impulses in the ordinary operation of the system. The switch 47 has also a third contact 47* which closes upon its other contact when the switch is in normal closed position and makes no effective contact when the switch is open, such additional and supplemental contact being for the purpose later to be described. The control by the sectors 26 and 26' is effected through the companion double throw switches 53 and 53', having an elongated central spring, and upper and lower contacts. The elongated said springs of the two switches are normally pressed upon by the insulating blocks 54 and 54' upon the respective sectors 26 and 26' so that they are maintained normally in contact with their lower contact points, but will spring to their upper contacts when freed.

The controlling circuit is as follows: from the positive terminal of the battery 16, by wire 56 to the center leaf of the switch 53'; by parallel branches 57 and 57' respectively from the lower and upper contacts thereof to the middle and lower contacts of switch 53; and by parallel wires 58 and 58' respectively from the upper and lower contacts of switch 53, the first said branch 58 including switches 47 and 45 and magnet 41; the remaining branch 58' including switches 47' and 45' and magnet 41'; and said parallel branches uniting and being connected by wire 59 with the operating circuit wire 20 at the cutout switch 21.

The parts so far described constitute complete means for effecting the true selective action of the selectors, whereby the selectors are successively potentiated for operation in response to properly succeeding line signals and for restoration to normal position in response to a single impulse following the completion of the calling operation. Thus it will be apparent that assuming the mechanism to stand in the position shown in Fig. 2, if the signal initiator be actuated to send say the number 33, consisting of three short interruptions in the line, a spacing pause, and three more interruptions in the line, fol-

lowed by a pause of any desired length of time to constitute a calling or ringing interval, and then a single short interruption of the line, the selectors will be actuated as follows: With each break in the line the armature 13 of the line relay makes contact with its back contact point 15, completing the operating circuit 16, 17, 18, 19, 20, 21, and 22, so energizing the operating magnet 19 upon each break in the line. With the first three operations of the armature 35, the bar 36 operates the live pawl arm 27 of the tens selector, advancing it three steps, the holding pawl 30 holding the sector 26 against return to normal position. It will be observed, however, that with the first step of the tens selector 25, the long spring of the double throw switch 53 in the controlling circuit is released and moves into contact with its upper point thereby shifting the operative connections of the controlling circuit from the "tens" or left side thereof to the "units" or right side thereof, as shown in Fig. 1. With the first step of the tens selector, therefore, the units branch of the controlling circuit would be closed except for the retarding action of the dash pot 49, which retards for a period greater than the impulse intervals the return of both the switches 47 and 47' to normal or closed position after each depression by the finger 50 connected to the bar 36 of the magnet 19. Accordingly, the actual closing of the units or right side of the controlling circuit does not occur as long as the tens selector is being stepped forward by short rapidly succeeding interruptions in the line, but as soon as the spacing pause occurs of a duration greater than the retardation effect of the dash-pot 49, both the switches 47 and 47' close and accordingly a complete controlling circuit is established from battery 16 as follows: 56, 53' (lower contact), 57, 53 (upper contact), 58', 47', 45', 41', 59, 21, and 22, thereby establishing an energized controlling circuit for the shifting magnet 41', which immediately throws over the armature 42 shifting therewith the bar 36 of the operating magnet 19 into position for cooperation with the live pawl of the units selector, and at the same time throwing over the fiber block 46 on the armature extension so that it opens the switch 45' and closes switch 45, thus breaking the units controlling branch immediately-before established and partially closing the tens controlling branch. Now when the second group of line interruptions constituting the second numeral is transmitted, the operating circuit is closed and opened as before described but the consequent movements of the armature of the operating magnet 19 affect the units selector 25'. With the first advance movement of the units selector, removing the pin 34' from the path of the 130

shifting bar 32, the holding pawl of the units selector comes into operation but the spring for the holding pawl of the tens selector is disabled or rendered inoperative by removal from engagement with the pawl 30. The pawl 30 does not, however, drop out of connection with its sector because of its frictional engagement with a sector tooth but temporarily remains inert. Also, the first movement of the sector 26' of the units selector 25' releases the long blade of switch 53' which immediately seeks its upper contact, breaking connection with its lower contact. This shifting of the switch 53' establishes a path through the left hand or tens side of the controlling circuit subject to the retarded action of the switch 47, which, as will be apparent, is retarded by the dash pot 49. Consequently, the several rapidly succeeding interruptions constituting the units digit, cause the units selector to be stepped forward an equivalent number of steps but as soon as the ringing pause comes, the controlling circuit for the tens branch is closed from battery 16 by path 56, 53' (upper contact), 57', 58, 47, 45 (now closed), 41, 59, 21, and 22, causing the magnet 41 to attract armature 42 and shift the shiftable bar 36 to initial position and opening the switch 45 while it again closes switch 45'. Now when, after the ringing interval, the single break occurs in the line, the magnet 19 causes the tens selector 25 to be stepped forward another step, but it cannot be retained in advanced position because with the commencement of the movement of the sector 26, the pawl 30 is released from frictional restraint and is moved by gravity back against its spring 31 which, it will be remembered, has been moved to the right by the advancement of the units pawl 30'. Consequently, as soon as the magnet 19 is de-energized following the releasing impulse, the sector 26 drops back to initial position, throwing switch 53 to original position, and pulling over the pawl bar 32, which drags the holding pawl 30 out of engagement with the sector 26' of the units selector, permitting the latter to drop back in turn to initial position and so restoring all of the before-mentioned parts to the normal condition first described.

It will be apparent that the devices described provide means for automatically shifting the mechanical connections of the operating magnet from one selector to another whenever, after precedent operation of the one selector a dwell occurs in the signaling operation such as transpires between the several impulse groups or parts of the signaling cycle.

The selectors above described are of course instrumentalities for co-operatively establishing an operating condition for some translating device or devices, the operation

of which constitutes a call and in the specific construction the translating devices may be sounding alarms, such as bells, the circuits for which are controlled by the selector devices. Specifically, the selectors 26 and 26' carry contact springs 61, 61', respectively, the former arranged for connection with contact 62, set at any appropriate point, and the latter coacting with two contacts 62' and 62'' appropriately spaced. In connection with the first mentioned contact 61, a small switch 63 may be arranged for closure only while the tens selector is on its first step, for purposes to be described.

In the circuit diagram disclosed, connection is made from the supplementary contact 47* of the switch 47, by wire 64 to two branches 65' and 65'', respectively including the bells 66' and 66'' and terminating in the contacts 62' and 62''. The two selectors 26 and 26' are connected by a conductor 67 (which may be the frame of the mechanism) and the contact 62 is connected, by wire 68, with wire 20 so that when the two selectors are properly collocated, a ringing circuit is established from battery 16 by the path 56, 53' (upper contact), 57', 58, upper spring of switch 47, 47*, 64, 66', 65', and 62' (or 66'', 65'', 62''), 61' 67, 61, 62, 68, 20, 21, and 22. The provision of the two bells 66' and 66'' is a refinement intended particularly for railroad signaling to enable the provision of one bell which as a rule may be used only by the train despatcher or other high official, and also to provide against failure of a call through a defect in the bell ordinarily used. Further to provide means for specially attracting the attention to the calls of the despatcher, I provide a bell 69, connected by wire 70, including the small switch 63, between the wires 64 and 68, for operation as hereinafter described.

The particular connection of the bells as described has the advantage that no bell will ring as the selector skips past the ringing contact in seeking a station of higher number, because the ringing circuit above described depends for its establishment upon the making of connection between the upper blade of switch 47 and the supplemental contact 47*, and such connection is broken at each operation of the operating magnet 19 and reestablishment is retarded by the dash pot 49.

The parts described constitute a complete and operative system, in which a plurality of selectors, intended for collocation to secure the response of a local translating device or alarm, are automatically responsive to like but separate signals initiated in the line, with which the local devices have connection only through the agency of a single relay, and in which the shifting device controlling the potentiation of the separate selectors for operation are subject to control

by the selectors; by timing or retarding mechanism; and by the shifting mechanism itself. As a part of the system, however, I prefer to employ means for preventing the wasting of the local battery in the event of a continued break in the main line, and means which will restore the selective parts to normal position after a predetermined length of time following a partial operation thereof, so that following the breaking and repair of a line or the grounding of a line between its ends, the selectors may all be in proper position, and so that the selectors may certainly be prevented from remaining out of step in the event that they should once become so through such abnormal grounding of the line or other cause.

The specific mechanism, which I employ in the embodiment illustrated, comprises a governor magnet 72, arranged to be thrown into energized circuit under certain conditions of operation of the system, a pair of switches controlled by said magnet, a timing mechanism for retarding the operation of said magnet in closing the switches, a positive releasing mechanism for the tens selector including a magnet controlled by one of said switches, a restoring magnet controlled by the other switch of the pair and by the armature 13 of the line relay, said restoring magnet in turn controlling the cutout switch 21. The governor magnet 72 has one terminal connected by wire 73 to the operating circuit wire 20 of the cutout switch 21, the other terminal being connected by wire 74 to a switch 75 which has in turn a connection 76 to wire 56, the switch 75 being arranged in conjunction with the armature 35 of the operating magnet 19 to be closed whenever the operating magnet is energized. The wire 74 has also a connection 77 to the lower supplemental spring 45* of the switch 45. Thus, whenever the operating magnet 19 is energized, a circuit for the governor magnet 72 is established from the battery through a path as follows: 56, 76, 75, 74, 72, 73, 21, and 22; and at any stage of the operation of the system, when the tens selector has operated and the units selector has not yet commenced to operate, a circuit for the governor magnet is established from battery 16 through the following path: 56, 53 (lower contact), 57, 53 (upper contact), 58', 47', elongated blade of switch 45', contact 45*, 77, 74, 72, 73, 21 and 22. Accordingly, upon the closure of either circuit described, the governor 72 is energized and pulls upon its armature 72' which works, in responding to such attraction, against the dash pot 78, the stem 79 of which when raised operates in tandem relation in point of time the switches 80 and 85. The former switch 80 has one of its blades connected by wire 81 to wire 56, its other blade being connected by wire 82 through the windings of a small magnet 83'

with the wire 20, so that whenever the switch is closed, a circuit for the magnet 83' is established from the battery 16 by the path 56, 81, 80, 82, 83', 20, 21, and 22. The magnet 83' has its armature 84 arranged when attracted positively to throw the holding pawl 30 for the tens selector 25 out of engagement with its sector 26, so that the energization of the circuit described produces a mechanical release of the tens selector from domination of its holding pawl. The remaining switch 85 has connection by wire 86 with the front contact 14 of the line relay 12, and its other blade has connection by wire 87 with the restoration magnet 88, the remaining terminal of which is connected by wire 89 with the wire 22, so that such restoration magnet 88 receives current when the line relay is energized and the switch 85 closed by the path from the battery 16 as follows: 17, 13, 14, 86, 85, 87, 88, 89, and 22. Normally the armature 89' for magnet 88 is held in attracted position mechanically by a latch bar 90 pivoted as at 91 and pivotally connected to the extremity of the extension 90 arm of the armature 72' which is connected to the dash pot pen 79. The armature 89' is also provided with a finger 92 which normally holds closed the cutout switch 21, but when the armature is released by its latch 95 and drops back to unattracted position, it opens the cutout switch. In timing factor, the apparatus described is so arranged that the dash pot retards the closure of the switches 80 and 85 for a very considerable time from a signaling standpoint, such say of five or ten seconds, but does not release the armature 89' from latched position until it has closed the switches. Then the pin 89' upon the armature 89' moves into the notch 105 90' of the latch 90 and latches the dash pot in raised or switch closing position, at the same time that it opens the line switch, provided the magnet 88 is not energized.

The operation of the releasing and restoring devices just described is as follows: Assume that there is a break in the line 10, deenergizing for a considerable time the line relay 12. Instantly upon the closure of the contacts 13 and 15 of the line relay, the operating magnet 19 responds to advance the tens selector one step, but then remains energized. As long as the armature 35 of the operating magnet is attracted, closing the switch 75, the governor magnet 120 receives current by path 56, 76, 75, 74, 72, 73, 21, and 22, and after the lapse of the predetermined time defined by the dash pot, the two switches 80 and 85 will be successively closed. This closure of switch 80 125 completes the circuit 16, 56, 81, 80, 83, 20, 21, and 22 of the magnet 83', but this energization of the relay 83' is ineffectual, for, although the holding pawl is momentarily moved away from its ratchet, the live pawl, 130

it will be remembered, is being maintained in sector-engaging position by the continued energization of magnet 19, thus preventing the return of the sector to initial position.

5 Almost immediately as the switches 80 and 85 are closed, however, the latch 90 moves out of the path of the pin 89", and permits the latter to pass into the notch 90' to latch the switches in closed position while the 10 finger 92 opens the line switch 21. This opening of the line switch deenergizes magnets 19 and 83' alike, and does not in practice release the sector 26, because the active spring 31 throws the holding pawl 30 back 15 into engagement with the sector before the sector can drop. It will be remembered, however, that switch 80 is locked closed. Later, when the line is repaired, and the 20 relay 12 is deenergized, throwing the armature 13 against the contact 14 and completing the circuit 16, 17, 14, 86, 85, 87, 88, 89, for the cutout controlling magnet 88, said magnet instantly responds to close the cutout switch 21 and release the latch arm 90, 25 so that the dash pot plunger may drop back to normal position. Before the switch 80 is opened, however, current flows through the reestablished circuit for the releasing magnet 83' and causes it again to throw out 30 of operative arrangement the holding pawl 30, this time dropping the selector back to initial position, because the magnet 19 remains deenergized and the live pawl stays in normal position. In the event a partial 35 signal only is sent, say the first group of numbers, advancing the tens selector but otherwise leaving the parts in normal condition with the local operating circuit open, the system is automatically restored to normal after a time determined by the dash 40 pot 78, in the following manner: The operation of the tens selector followed by a short pause causes the controlling mechanism to shift to potentiate the units selector, as has 45 been heretofore described, and in so doing the elongated blade of switch 45' falls into contact with point 45". This establishes a circuit for the governor magnet 72 as follows: 16, 56, 53' (lower contact), 57, 53 50 (upper contact), 58', 47', elongated blade of switch 45', contact 45", 77, 74, 72, 73, 21 and 22, so that after the predetermined time of retardation of dash pot 78, the switches 80 and 85 are closed as before described. The 55 switch 80 closes first and consequently the magnet 83' is energized and pushes the holding pawl 30 out of engagement with the sector 26, permitting said sector 26 to drop to initial position, so establishing the circuit, 60 through the left hand or tens branch of the controlling circuit and causing the shifting mechanism to shift back to normal position and opening the circuit for the governor magnet 72 at the contact 45", so that immediately afterward, when the switch 85 closes

and the magnet 88 receives current (armature 13 being forward against contact 14) the momentarily opened cutout switch is closed again, the dash pot 78 allowed to return to normal position and the whole system restored to normal. I have found that in this way the selectors are prevented from ever getting out of step in the sense of getting into such inharmonious relation that the units selector responds to a tens number, 75 and so on; yet the time limit of the dash pot 78 has no effect on ordinary ringing operations, for as soon as the units selector is stepped forward both of the alternative circuits for governor magnet 72 are broken, 80 the one at the lower contact of switch 53' and the other at switch 75, thereby disabling said governor magnet. Where the self restoring devices described are not employed, however, no selector apparatus can continue out of step for more than two complete 85 signal cycles, in any event.

While, as I have herein indicated, the system may be worked through any manually operable circuit closing device, such as the telegraph key, I preferably use at each station a motor-driven transmitting box which may be set for the sending of any desired number signal. To this end, I preferably employ a motor-driven transmitter 95 adapted to be manually wound for a single round, comprising two coincidently driven disks 96 and 96' bearing rotarily-adjustable toothed sectors 97 and 97' respectively, movable for predetermined cooperation with line breaking switches 98 and 98', and one of the disks bearing a permanent tooth 97" for cooperation with one such switch. A suitable arrangement of one of the sectors on its disk is shown in Fig. 105 96, the sector 97 being normally removed vertically from the disk by spring 99 but arranged to be depressed upon the disk in any position permitted by the cooperation of the pin 100 upon the sector with holes 101 in the disk, and latched in depressed or operative position by a latch mechanism 102, which is arranged to be released by a trip 103 at any desired point in the rotation of the disk. The mechanisms for both disks 110 may be similar, but the relative arrangement of the sectors and line opening switches is such that the sector of the tens disk 96 may be set with any desired number of teeth back of the switch 98, by their 115 passage to transmit the tens number; while the sector 97' for the units disk 96', may be set subsequently to occasion any number of its teeth to pass a switch before the releasing mechanism operates to permit the sector to be spring-pressed in inoperative position. Then, after a pause, the single tooth 97" 120 will cause the restoring break to occur. As a refinement, further, the train despatcher or other party whose call should receive special 130

attention may have his transmitter with an auxiliary switch 105, arranged when manually depressed to be held by a latch 106 in open position and released for spring-return to closed position by tripping of latch 106 by the winding handle 107 of the box. Thus when the train despatcher, for example, wishes to send a signal and to insure that his call will take precedence over the business of any other party on the line, he depresses the manual key 105 before he starts to set his transmitter to send the number required. The opening of the line results in the stepping up of the tens selector one step throughout the line and thereby closing at each station the circuit of the small bell or buzzer 69 which rings during the interval of time until the automatic restoration mechanism operates as has been heretofore described to throw the apparatus back to normal position, say five seconds. Then when the operator, having set his box, pulls the winding handle to potentiate the box for operation, the manual switch 105 is tripped and allowed to return to closed position and the line is ready for ordinary signaling.

While I have herein described in some detail a specific embodiment of my invention, it will be apparent to those skilled in the art that many changes might be made in the particular embodiment without departure from the spirit and scope of my invention.

35 What I claim is:

1. In a signaling system, the combination with a line provided with means of current supply and signal initiating means, of station apparatus comprising means responsive to the line condition, a plurality of selectors adapted for successive operation, means for potentiating said devices successively for operation in response to the line responsive means, and translating means responsive to predetermined collocation of the selectors.

2. In a selective signaling system, the combination with a line provided with means of current supply and signal-initiating means, of a station apparatus comprising means responsive to the line conditions; a plurality of selectors, one normally in coöperative relation with said line-responsive means for operation in response thereto; means controlled by each selector for potentiating the succeeding selector for such response to the line responsive means, and a translating device responsive to predetermined collocation of the selectors.

3. In a selective signaling system the combination with the line provided with means of current supply and signal initiators, of a station apparatus comprising means responsive to the line conditions, a plurality of selectors for control thereby, means con-

trolled by one of said selectors for potentiating another for operation, means retarding the operation of the last said means, and a translating device responsive to predetermined collocation of the selectors.

4. In a signaling system, the combination with the line, means of current supply, and signal initiators therein, of station apparatus comprising means responsive to the line condition, a plurality of selective devices for operation thereby, means controlled by each selector for potentiating the next selector to operate, means for retarding the operation of the last said means, and translating devices responsive to predetermined collocation of the selectors.

5. In a selective signaling system, the combination with a line provided with means of current supply and signal initiating devices, of a single line relay, a plurality of selectors for operation in response thereto, means controlled by each selector for operatively associating the next succeeding selector with said relay for response to said relay, means for retarding the operation of the last said means for each selector, and a translating device operable in response to predetermined collocation of the selectors.

6. In a selective signaling system, the combination with a line provided with means of current supply and signal initiating devices, of a station apparatus comprising a plurality of selectors, translating means responsive to predetermined collocation of the selectors, means associated with the line for operating any potentiated selector, means for holding the selectors in operated positions, and means for successively potentiating said selectors for operation and subsequent release in response to a series of signals initiated in the line.

7. In a selective signaling system, a line provided with means of current supply and signal initiators, and station apparatus comprising a relay in the line, a local operating circuit with connections controlled by said relay, a plurality of selectors, operating means therefor in said operating circuit, means for holding them in operated positions, and local-circuit controlling means for potentiating said selectors successively for operation and subsequently for release in response to movements of said operating means.

8. In a selective signaling system, the combination of a line; means of current supply therefor; and at each station signal initiating means; a line relay; local selective apparatus comprising a plurality of selectors, electro-responsive operating means therefor, and a local operating circuit controlled by the line relay; electro-responsive controlling means for potentiating each selector for operation by its operating means;

local controlling circuit connections for the controlling means of each selector, controlled by the selector to be precedently potentiated; and translating devices arranged to respond to predetermined collocation of the selectors.

9. In a selective signaling system, a line circuit, means of current supply therefor, and at each station signal initiating means and means responsive to the condition of the line, combined with local station apparatus comprising a plurality of selectors, translating devices responsive to predetermined collocation of said selectors, means for operating said selectors including an operating circuit controlled by the line responsive means, controlling apparatus for potentiating said selectors for operation in response to their operating means in predetermined sequence, electrical connections for said controlling apparatus, means controlled by each selector effecting the potentiation of the succeeding selector, and means for definitely retarding the potentiation of each selector.

10. In a selective signaling system, the combination of a line, means of current supply therefor, signal initiating means, and at each station means responsive to the condition of the line, a plurality of selectors, electro-responsive operating means for said selectors, circuit connections therefor controlled by the line responsive means, a shiftable part arranged for movement successively to potentiate the selectors for operation in response to their operating means, and means for moving said shiftable means controlled as to its action to potentiate each selector by the condition of the precedently-operable selector.

11. In a selective signaling system, the combination of a line circuit, a source of current supply therefor and signal initiating means at each station, and means responsive to the condition of the line, a local operating and releasing circuit at said station controlled by the line responsive means, common selector operating and releasing means controlled by said local operating circuit, selectors to be successively operated, means for holding said selectors in operated positions, and means for automatically placing said selectors successively in co-operative relation with said operating means for successive operation and subsequent release in response to movements of their common operating means.

12. In a selective signaling system, the combination of a line, means of current supply therefor, and at each station signal initiating means and means responsive to the condition of the line, a local operating circuit controlled by said line responsive means, selector-operating means in said operating circuit, a plurality of selectors, means for

successively placing each selector in co-operative relation with said operating means for operation in response to movements of the operating means including for each selector a controlling circuit; means for establishing said controlling circuits in predetermined sequence; and means for timing with reference to the operating means the establishment of any said controlling means.

13. In a selective signaling system, the combination of a line, means of current supply therefor, and at each station signal initiating devices and means responsive to the condition of the line; a local operating circuit controlled by said line responsive means, selector operating means in said operating circuit; two selectors, adapted for successive operation, means for holding said selectors in operated positions, translating means responsive to predetermined collocation of the selectors; means controlled by the primary selector for potentiating the secondary selector; means controlled by the secondary selector for potentiating the primary selector for further operation, and means whereby further operation of the primary selector releases both selectors.

14. In a selective signaling system, the combination of a line, means of current supply therefor, and at each station signal initiating devices, and means responsive to the condition of the line; a local operating circuit controlled by said line responsive means; selector operating means in said operating circuit; two selectors adapted for successive operation, translating means responsive to predetermined collocation of the selectors, means controlled by the primary selector for potentiating the secondary selector, means controlled by the secondary selector for potentiating the primary selector for further operation; and mechanical connection between the selectors whereby the operation of the secondary selector conditions both selectors for restoration to normal position upon the subsequent operation of the primary selector.

15. In a selective signaling system, a line, means of current supply therefor; and at each station a signal initiator; means responsive to the condition of the line; a local operating circuit controlled by said line responsive means, selector operating means in said operating circuit; a plurality of selectors adapted for successive operation; electro-responsive controlling means for each selector for potentiating the same for operation; controlling circuits for said controlling responsive means; switches in each of said controlling circuits, one controlled by the precedently-operable selector, and another controlled by the movements of the selector-operating means, and means for timing the operations of the switches last mentioned.

16. In a selective signaling system, a line, means of current supply therefor, and at each station signal initiating means, and means responsive to the line condition; a local operating circuit controlled by said line responsive means; selector operating means in said operating circuit; two selectors adapted for successive operation, translating means responsive to predetermined collocation of said selectors, means whereby the successive operations of the primary and secondary selectors condition them for mutual restoration to normal condition upon a subsequent further operation of the line responsive means, means controlled by the primary selector for potentiating the secondary selector and disabling itself, and means controlled by the secondary selector for again potentiating the primary selector.
17. In a selective signaling system, a line, means of current supply therefor, signal initiating means, and means responsive to the line conditions, a plurality of selective devices, means for potentiating said devices successively for operation in response to the line responsive means, translating devices responsive to predetermined collocation of the selectors, and means timed in operation for restoring the selectors in normal position after the operation thereof.
18. In a selective signaling system, a line, means of current supply therefor, signal initiating means, and at a station means responsive to the line conditions, a plurality of selectors, operating means for said selectors, a local operating circuit containing said operating means and controlled by the line responsive means, means for potentiating said devices successively for operation in response to their operating means, and means for opening said operating circuit after a continuous closure thereof for a predetermined time.
19. In a signaling system, a line, means responsive to signals in the line, a plurality of selectors, translating means responsive to predetermined collocation of said selectors, and means for automatically placing the first named means successively in cooperative relation with the said selectors for successive operation thereof.
20. In a signaling system, a line, a signal initiator therein, a plurality of selectors, translating means responsive to predetermined collocation of said selectors, means responsive to line signals for operating said selectors, and means for automatically placing the line-signal-responsive means suc-
- cessively in cooperative relation with said selectors for successive operation thereof, and for restoring said selectors to initial position upon completion of a signaling cycle.
21. In a signaling system, a line, a signal initiator, a plurality of selectors, means responsive to line signals for operating said selectors, means for automatically placing the line-signal-responsive means successively in cooperative relation with said selectors for successive operation thereof, the last said means including a shiftable pawl operating mechanism shifted during intervals between the impulse groups of a signal cycle.
22. In a signaling system, a line, a signal initiator, station apparatus comprising a plurality of selectors, translating means responsive to predetermined collocation of said selectors, an operating magnet arranged for response to signals in the line, operable connection-means between said magnet and the several selectors, and means for affecting said connection-means to place the operating magnet successively in cooperative relation with said selectors for successive operation thereof.
23. In a signaling system, a line, an operating magnet arranged for response to signals in the line, a plurality of selectors, shiftable mechanism for connecting any selector to the operating magnet, and means for shifting said mechanism to bring said selectors in succession into operative connection with the operating magnet.
24. In a signaling system, a line, a signal initiator in the line operable to transmit a signal cycle such as a plurality of number groups and a releasing impulse, a station apparatus comprising a plurality of selectors, a translating device responsive to predetermined collocation of said selectors, a common selector-operating magnet responsive to line signals, means, timed for operation in harmony with the number groups of a signal cycle, for successively placing the selectors in cooperative relation with the signal-responsive operating magnet for operation thereby, whereby each selector responds to its appropriate number group, and means for restoring to normal position the selectors, responsive to the releasing impulse.
- In testimony whereof I hereunto set my hand in the presence of two witnesses.
